UNITED STATES PATENT OFFICE.

ALFRED WENNING AND CHARLES HUBERT GÉGAUFF, OF MULHOUSE, GERMANY, ASSIGNORS TO THE FIRM OF SOCIÉTÉ ALSACIENNE DE CONSTRUCTIONS MÉCANIQUES, IN MULHOUSE, GERMANY.

COMBING-MACHINE.

SPECIFICATION forming part of Letters Patent No. 787,139, dated April 11, 1905.

Application filed October 21, 1902. Serial No. 128,175.

To all whom it may concern:

Be it known that we, ALFRED WENNING and CHARLES HUBERT GÉGAUFF, subjects of the Emperor of Germany, and residents of Mulhouse, Alsace, Germany, have invented new and useful Improvements in Combing-Machines, of which the following is a full, clear, and exact specification.

The present invention is designed for combing-machines, and has for its object considerably to simplify the labor of the operative or to enable the number of machines which can be attended by one operative to be increased, and thereby to diminish the expense of labor. In those machines hitherto known the combing or waste is collected in a box underneath the same, and this box must be very often emptied—every five minutes or so—which is very troublesome, because the combings collect in it in a fluffy condition. In order to avoid this frequent emptying of the collecting-box, the following device has been invented, in which the combing or waste is automatically pressed down in the box until it is in a very powerfully-compressed state. Consequently the collecting-box only requires to be emptied comparatively seldom—about every two or four hours. For this purpose the box has a partition at the filling-aperture, reaching up to close against the periphery of the doffing-rollers, so-called “doffer,” while the stripping-blade or scraper forms, with its support, another box-wall lying opposite the first one, so that to a certain degree the doffing-roller and the stripping-blade themselves form the compressing organs.

The accompanying drawing illustrates the present invention as applied to a combing-machine of the Heilmann type, of which machine only the head is illustrated.

In the drawing, A indicates the feeding-nipper of the machine; B, the rotary combing-cylinder; C, the brush for brushing off the combing-cylinder; D, the taking-off roller or doffer, with its card-like covering, which transports the material delivered by the brush, and E the oscillating stripping-blade or scraper,

all of which form well-known parts of the Heilmann machine. Underneath the roller D is placed the collecting-box F for the combings or waste. This box has at the top a sloping wall f, which is placed close to the covering of the doffer D, while the scraper E is supported by a plate e, which rests on the oscillating shaft G and forms a further inclosure of the collecting-box in such a manner that the whole forms a space inclosed by the walls f e and the doffer D.

The combings which are continuously removed from the comb-cylinder by means of the brush C are delivered by it to the doffer D, because the combings remain hanging from the card-teeth, covering the same. The combings are transported by the doffer D to the point a near the oscillating scraper E, where the said scraper removes them from the doffer, and the combings fall down, owing to their weight. When the box is thus lightly filled, the compression of the fluffy mass of combings commences, because, on the one hand, the freshly-delivered combings tend to press the others down in order to make room, and there is nowhere any opening whereby they can escape from the box, and, on the other hand, the combings cannot pass farther with the doffer than up to the separating-point a, at which point the oscillating scraper E in front of the doffer obliges them to remain. Consequently after a certain time the mass of combings in the box are reduced to a strongly-compressed state. In order to empty the collecting-box F thus filled, it is only needful to open the front door g, which door is arranged to open outward, as shown by dotted lines.

In order automatically to remove the dust which constantly forms in the front of and around the brush C, there is placed before the brush a polished guard-sheet H, which is partly perpendicular and partly inclined and reaches down to the box-wall f. In consequence of the position of this sheet and the quivering motion thereof during the working of the machine the dust intercepted by the sheet H slips continuously down its smooth in-

ner wall and is consequently finally seized by the doffing-roller D and driven into the collecting-box F.

What we claim is—

- 5 1. In a combing-machine, the combination with the doffer, of a receptacle below the doffer for the combings removed therefrom, said receptacle having a relatively narrow receiving-inlet *a*, a downwardly-inclined plate *f* at one side of said inlet, and a hinged, vibrating plate *e*, provided with a scraper *E*, at the opposite side of said inlet, the movements of said vibrating plate being toward and from the inclined plate *f*, substantially as and for the purpose set forth.
- 10 2. In a combing-machine, the combination with the combing-cylinder, the brush C, and
- 15

the doffer, of the receptacle F, having the downwardly-inclined plate *f* at one side of the inlet and the vibrating plate *e* at the opposite side of said inlet, the scraper on said plate *e*, and the plate H, extending from the upper edge of the plate *f* upwardly about the doffer and the brush, substantially as and for the purpose set forth. 25

In witness whereof we have hereunto signed our names in the presence of two subscribing witnesses.

ALFRED WENNING.

CHARLES HUBERT GÉGAUFF.
